UNITED STATES PATENT OFFICE.

ANDREW G. STEINBRENNER, OF ST. LOUIS, MISSOURI, ASSIGNOR TO THE WESTERN RAILWAY EQUIPMENT COMPANY, OF EAST ST. LOUIS, ILLINOIS.

DESIGN FOR A DRAFT-LUG AND DRAW-BAR FOLLOWER.

SPECIFICATION forming part of Design No. 25,957, dated August 18, 1896.

Application filed July 15, 1896. Serial No. 699,328. Term of patent 14 years.

To all whom it may concern:

Be it known that I, ANDREW G. STEINBRENNER, a citizen of the United States, residing at the city of St. Louis, State of Missouri, have invented a new and original Design for Draft-Lug and Draw-Bar Followers, of which the following is a full, clear, and exact description, such as will enable others skilled in the art to which it appertains to make and use the same, reference being had to the accompanying drawings, forming a part of this specification, in which—

Figure 1 is a top plan view. Fig. 2 is a front elevational view. Fig. 3 is a side elevational view, and Fig. 4 is a rear elevational view.

This design relates to a new and original design for a draft-lug and draw-bar follower; and it consists in the shape and ornamentation of the same, as will hereinafter be more fully described.

In the drawings, A indicates the front wall, which is formed with an opening about its center and has extending forwardly from near its upper side edges projections a, whose upper, lower, and inner faces are curved, the sides being on the same plane as the side walls.

B indicates the side walls, which are formed

with vertically-disposed ribs or projections b and b', the former being slightly larger than the latter, while between these ribs are openings or perforations b''.

C and D indicate the top and bottom walls, which are cut away at the rear, as shown. The top wall C has a T-shaped projection at its forward edge, the cross of the T being substantially in the same plane of the front wall A. This T is highest at the junction of the cross, from which it gradually falls to the plane of the top wall. The rear end is open, and a ring a' surrounds the opening a.

E indicates webs or flanges, which radiate from said ring to the top, bottom, and side walls.

What I claim is—

The design for draft-lugs and draw-bar followers, substantially as herein shown and described.

In testimony whereof I hereunto affix my signature, in presence of two witnesses, this 6th day of July, 1896.

ANDREW G. STEINBRENNER.
